CLAIM

The ornamental design for an appliance knob, as shown and described.

DESCRIPTION

FIG. 1 is a front perspective view of an appliance knob showing our new ornamental design;

FIG. 2 a front view thereof;

FIG. 3 is a top view thereof;

FIG. 4 is a bottom view thereof; and,

FIG. 5 is a left side view thereof, with the right side view thereof being a mirror image thereof.

The views of the appliance knob not shown (e.g., rear view), form no part of the claimed design.
